(57) **CLAIM**

The ornamental design for a lamp, as shown and described.

DESCRIPTION

FIG. 1 is a perspective view of a first embodiment of a lamp showing my new design;

FIG. 2 is a right side view thereof, the left side view being a mirror image;

FIG. 3 is a front view thereof, the rear view being a mirror image;

FIG. 4 is a top plan view thereof;

FIG. 5 is a bottom plan view thereof;

FIG. 6 is a perspective view of a second embodiment of a lamp showing my new design;

FIG. 7 is a right side view thereof, the left side view being a mirror image;

FIG. 8 is a front view thereof, the rear view being a mirror image;

FIG. 9 is a top plan view thereof; and,

FIG. 10 is a bottom plan view thereof.

FIGS. 1-3, and 6-10 include break lines and those portions of the article between the break lines form no part of the claimed design. The short broken lines represent environmental subject matter and form no part of the claimed design.

1 Claim, 6 Drawing Sheets
